CLAIM

The ornamental design for a face shaped packaging, as shown and described.

DESCRIPTION

FIG. 1 is a perspective view of a face shaped packaging showing the claimed design;

FIG. 2 is a bottom perspective view thereof;

FIG. 3 is a front view thereof;

FIG. 4 is a back view thereof;

FIG. 5 is a side view thereof;

FIG. 6 is a side view thereof;

FIG. 7 is a bottom view thereof;

FIG. 8 is a top view thereof; and,

FIG. 9 is a perspective view thereof with the headband portion removed for ease of illustration.

The broken lines in the drawings depict portions of the face shaped packaging and form no part of the claimed design.
